UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

LAMP-HOUSE FOR MOVING-PICTURE MACHINES.

1,383,753.

Specification of Letters Patent.

Patented July 5, 1921.

Application filed June 6, 1916, Serial No. 102,072. Renewed December 7, 1920. Serial No. 429,035.

To all whom it may concern:

Be it known that I, NICHOLAS POWER, a citizen of the United States, and a resident of the borough of Brooklyn, city, county, 5 and State of New York, have invented new and useful Improvements in Lamp-Houses for Moving-Picture Machines, of which the following is a specification.

This invention relates to lamp-houses for 10 arc lamps of the character used for the projection of motion pictures, and has for its object to provide a lamp house in which a high powered arc can be used with perfect safety and so designed that no part of the 15 lamp house becomes sufficiently heated to burn the operator, or ignite the film in case of accidental contact therewith.

More particularly the invention consists 20 of an improvement on the lamp house disclosed in my prior application No. 55,408 filed October 12, 1915, and embodies a design and arrangement of parts whereby a more uniform circulation of air through the lamp house is secured, and also means 25 whereby the front and top walls particularly are protected from the intense heat of the lamp. These walls are the ones that receive most of the heat from the lamp, the arc being much nearer the front than the back. 30 Moreover, these walls are more liable to come into accidental contact with the film and it is essential that they be maintained at a low temperature.

My invention also embodies an arrangement 35 of condensers whereby the lamp may be used as a spot-light when not used for the exhibition of pictures, and to this end the invention comprises an arrangement of condensers upon a movable wall of the lamp 40 house so that the projecting condensers may be swung out of the way and a special spot-light condenser inserted in a moment's time.

In the accompanying drawings, I have 45 illustrated a preferred design of my improved lamp house, and in said drawings,

Figure 1 is a vertical section through the lamp house showing the arc lamp in dotted lines;

Fig. 2 is a vertical section of the lamp 50 house alone at right angles to Fig. 1;

Fig. 3 is a sectional detail view of the front of the lamp house; and

Fig. 4 is a detail view of the detachable condenser for use with the lamp as a spot- 55 light.

Referring to the drawings, 1 indicates the base of the lamp house here shown as consisting of the usual carriage adapted to run on the track rods 2 of the supporting stand. The lamp house is made of sheet 60 metal in the usual manner and as here shown is of rectangular cross-section with doors 3 in either side wall. The front wall of the lamp house is formed of two spaced sheets, the front sheet 4 supporting the condensers 65 5 by which the light is centered on the film. The rear sheet 7 of the front wall is spaced slightly back of the front sheet to provide an air circulating channel extending the full height of the lamp house. The condensers 5 and the funnel 6 are carried by a hinged portion 8 of the front wall 4 as indicated more particularly in Fig. 3, whereby the condensers may be swung entirely clear 70 of the front of the lamp house. The condensers 75 comprise the usual pair of lenses, the rear lens being adjustably supported on upper and lower rods 9 for movement toward and from the front lens through the agency of an adjusting screw 10 mounted 80 for rotation in the door 8 and threaded into an eye on the rear lens-holder. The rear lens-holder projects into a central hole formed in a cast lens housing 11 supported in the rear sheet 7 of the front wall, as 85 shown in Fig. 1.

The upper part 12 of the lamp house is also formed with double walls and as shown is preferably formed as a cap or roof telescoping on the upper edge of the side and 90 end walls of the lamp house. The front sheet 4 of the front wall and the rear and side walls of the lamp house are beaded to provide a shoulder 13 supporting the lower edge of the upper part 12 and these walls 95 terminate slightly above the shoulder 13, as indicated. The rear sheet 7 however is continued above the other walls and is turned backward in a curved tongue 14 which registers with the middle partition 15 of the roof 12 to divide the space within the roof into two separate passages. The lower wall 16 of the upper part fits over the edges of the rear and side walls and extends but part way across the top of the main portion of 100 the lamp house to provide an opening for the escape of the hot air in the lamp house. The middle wall 15 extends from the tongue 14 to the rear wall of the upper portion or hood 12 and is provided at the rear with a 110

circular opening entering the short flue 17 which projects through the top wall 18, here shown as of angular shape with a middle bridge like a gable roof. The space between the walls 15 and 18 communicates with the space between the front sheets 4 and 7 of the front wall and also with the flue 17 through a hole 19 cut in the wall of the flue whereby an entirely independent circulation of air is maintained between the front walls of the lamp house and through the condensers, etc.

Air is admitted to the space between the front walls through a bottom opening 20 and air is admitted to the main compartment of the lamp house through a bottom opening 21 and also through the side openings 22 above and below the doors, the side openings being of substantially the same construction as shown in my co-pending application above referred to.

The doors 3 are also double-walled as shown in my co-pending application, but as here shown the outer sheet of the door is flat and the inner one recessed or offset to provide the space between the sheets forming the walls of the door. The outer walls are provided with upper and lower rows of perforations 23 for providing an independent circulation of air through each door.

The lamp, which I have indicated in dotted lines at 24, is supported in the usual manner on the usual carriage carried by lugs formed on the base 1 and projecting through holes in the sheet metal bottom of the lamp house proper. The adjusting screws, some of which I have indicated diagrammatically, project through holes in the rear walls of the lamp house to permit the lamp to be trimmed without opening the doors.

To permit the lamp to be used as a spot-light I preferably provide a single condenser or lens, indicated at 25, supported in a hanger 26 shaped to fit the front face of the casting 11 and having a grip-operated catch 27 adapted to clamp over the edge 28 of the lower fixed part of the front wall 4 when the door 8 supporting the projecting condensers, etc., is opened. To use the lamp for this purpose, the lamp house is shifted on the tracks 2 beyond the projecting mechanism and the door 8 is swung open wide so that the spot-light lens may be clamped in place in the manner indicated in Fig. 4. For this purpose the lamp house will be used in conjunction with a supporting stand such as shown in my prior application No. 55,409, filed October 12, 1915, wherein the lamp house carrying portion of the stand is swiveled to the base portion for adjustment thereon, a clamp being provided for locking the parts in their adjusted positions. To use the lamp as a spot-light the clamp is loosened so that the operator may swing the lamp house on its swivel joints to cause the

light to follow the movements of the actor on the stage.

In operation the heat from the lamp causes a circulation of air through the main compartment of the lamp house and out through the flue 17. This heated air heats the wall 15, producing an upward circulation through the front passage between two walls of the lamp house. Also the passage of air through the flue 17 across the opening 19 produces a suction in the upper passage of the hood, increasing the circulation through the front and top passages. By separating the outside front and top walls completely from the lamp-containing compartment, they are protected from the heat of the lamp and are heated only by the air through the passage-way, and if the circulation is sufficiently rapid the walls will not become heated to a temperature sufficient to ignite the film. As the only portions of the side walls close enough to the lamp to be heated are the doors whose outer walls are prevented from overheating by the independent circulation of air through the doors, there is no portion of the lamp house which can become hot enough to ignite the film in case of accidental contact of the film with the heated lamp house.

If desired the lowermost horizontal wall 16 may be omitted to permit the air from all parts of the interior of the lamp house to pass directly into the flue 17. The purpose of this wall with the opening near the front of the lamp house is to draw the air toward the front where the heat is greatest, but with the auxiliary passages between the front and top walls of sufficient size the outside walls will be kept sufficiently cooled without using the inner wall 15.

I claim:

1. A lamp house for projecting lamps consisting of a box-like housing inclosing the lamp, one wall of said housing consisting of two spaced sheets forming a passage for air circulation therebetween, said walls being formed with registering apertures for the passage of the light rays from the housing, a pair of condensers supported in said apertures, said condensers being spaced apart and with the space between them communicating with the space between the two sheets of the wall, and air ingress and egress openings to said passage.

2. A lamp house for projecting lamps consisting of a box-like housing inclosing the lamp, one wall of said housing consisting of two spaced sheets forming a passage for air circulation therebetween, said walls being formed with registering apertures for the passage of the light rays from the housing, a pair of condensers supported in said apertures, said condensers being spaced apart and with the space between them communicating with the space between the two sheets

of the wall, an air ingress opening leading from the outside air into said passage and an egress opening from said passage directly to the outside air, thereby providing for the circulation of air through said passage independently of the lamp-containing compartment of the housing.

3. A lamphouse for projecting lamps consisting of a housing inclosing the lamp, one wall of said housing consisting of spaced sheets providing a passage for air circulation therebetween, a movable support for the condenser lenses carried by the outer one of said spaced sheets, said inner spaced sheet having an opening in a portion adjacent said support, and condenser lenses mounted on said movable support and designed to project into and substantially fill the opening in said inner sheet, said passage having ingress and egress openings for the circulating air.

4. A lamphouse for projecting lamps consisting of a housing inclosing the lamp, one wall of said housing consisting of spaced sheets providing a passage for air circulation therebetween, said outer sheet comprising a hinged portion, said inner spaced sheet having an opening in a portion adjacent said hinged part, and condenser lenses mounted on said hinged part and designed to project into and substantially fill the opening in said inner sheet, said passage having ingress and egress openings for the circulating air.

35. 5. A lamphouse for projecting lamps consisting of a box-like housing having one wall formed of spaced sheets, condenser lenses supported by said wall arranged to substantially close communication between the space between said sheets and the lamp-containing compartment, air ingress openings in said lamp house adjacent each face of the inner sheet of said wall, and egress passages for said lamp-containing compartment and said space arranged to maintain a circulation of air along each face of said inner wall to thereby protect the condensers against excessive heating.

6. A lamphouse for projecting lamps consisting of a box-like housing having one wall formed of spaced sheets, condenser lenses supported by said wall arranged to substantially close communication between the space between said sheets and the lamp-containing compartment, air ingress openings in said lamphouse adjacent each face of the inner sheet of said wall, said lamphouse having a top portion provided with upper and lower air passages communicating respectively with said lamp-containing compartment and said air passage respectively.

7. A lamphouse for projecting lamps consisting of a box-like housing having double-walled doors on each side occupying the major portion of the wall area adjacent

the lamp, said housing having a double front wall, condenser lenses supported thereby, air ingress passages adjacent the bottom of said housing into said lamp-containing compartment and the space between the two sheets of the double front wall, a top detachably supported on said housing, said top having upper and lower passages communicating respectively with the space between the sheets forming the double front wall and the lamp-containing compartment, said passages having egress openings adjacent the top of the lamp whereby independent air currents will be maintained through the lamp compartment and also through the passage between the two sheets of the front wall.

8. A lamphouse for projecting lamps consisting of a housing having a base portion, front and rear walls and side walls connected to said base portion, said front wall comprising spaced sheets providing a passage for the circulating air separate from the lamp-containing compartment, condensers supported in said passage, a top detachably mounted on said front and rear wall, said top having a portion communicating with the lamp compartment, and a division plate forming a separate upper portion, said division plate adapted to register with the inner sheet of said double front wall when the top is in place, said separate upper portion having an egress opening at the opposite end of said division plate whereby the heat absorbed by said division plate will heat the air in said upper portion and produce a circulating draft between the two sheets of the front wall of the housing.

9. A lamp house for projecting lamps which consists of a housing inclosing the lamp, said housing having a detachable upper portion formed of three spaced walls, the bottom wall having an opening communicating with the lamp-containing compartment and the space between the lower wall and the middle wall having an egress opening into the outer air, whereby the air heated in the lamp compartment is kept out of contact with the top wall of the housing.

10. A lamp house for projecting lamps which consists of a housing inclosing the lamp, said housing having a detachable upper portion formed of three spaced walls, the bottom wall having an opening communicating with the lamp-containing compartment and the space between the lower wall and the middle wall having an opening into a flue to the outside air, the space between the middle and top walls also having an opening in said flue, and a separate ingress passage for air into the space between the middle and top walls.

11. A lamp house for projecting lamps which consists of a housing inclosing the

lamp, said housing having a detachable upper portion formed of three spaced walls, the bottom wall having an opening communicating with the lamp-containing compartment and the space between the lower wall and the middle wall having an opening into a flue to the outside air, the space between the middle and top walls also having an opening in said flue, the front wall of said housing being composed of two separate spaced sheets with the space between them communicating with the space between the upper and middle walls of the top portion and an opening into said space at the bottom thereof whereby a circulation of outside air is maintained between the front and top walls of the lamp house and the lamp-containing compartment.

12. A lamphouse for projecting lamps

consisting of a housing having a double front wall formed of spaced sheets, the outer of said sheets having a hinged portion, said inner sheet having an opening adjacent said hinged portion, condenser lenses supported on said hinged portion adapted to project into and substantially fill said opening and an auxiliary lens adapted to substantially fit said opening in the inner wall, said lens having supporting means adapted for detachable engagement with the stationary portion of the outer sheet of said wall when said hinged portion is swung open.

Signed at New York city, in the county of New York and State of New York, this 19th day of May, 1916.

NICHOLAS POWER.
